C. R. FORD.

BILGE WATER ALARM,

APPLICATION FILED SEPT. 22, 1915.

1,216,678.

Patented Feb. 20, 1917.

UNITED STATES PATENT OFFICE.

CHARLES R. FORD, OF PADUCAH, KENTUCKY.

BILGE-WATER ALARM.

1,216,678.

Specification of Letters Patent. Patented Feb. 20, 1917.

Application filed September 22, 1915. Serial No. 51,966.

To all whom it may concern:

Be it known that I, CHARLES R. FORD, a citizen of the United States, residing at Paducah, in the county of McCracken and State of Kentucky, have invented certain new and useful Improvements in Bilge-Water Alarms, of which the following is a specification.

This invention relates to devices for indicating the depth of water in the hold of a vessel and to sound an alarm when the water reaches a predetermined height.

The object of the invention is to provide a device which will be simple in construction, composed of very few parts, and efficient in operation to sound an alarm and indicate in what part of the vessel the high water is located.

The stated object and other incidental objects of the invention are attained in an apparatus of the type disclosed in the accompanying drawings, and the invention resides in certain novel features which will first be fully described and then more particularly pointed out in the claims.

In the drawings:

Figure 1 is a view partly in section and partly in elevation of my improved apparatus, the said figure being somewhat diagrammatic in its nature;

Fig. 2 is an enlarged detail vertical sectional view of the movable indicator member.

In carrying out my invention, I employ a hollow standard or tubular post 1 which is secured in a bracket or base plate 2 rigidly secured upon the deck of the vessel. This post or standard may be opened or closed at its upper end, as may be preferred, and is constructed with a longitudinal slot 3 through which the indicator finger may play. Along one side of said slot, I provide a series of graduations 4 which will indicate the height of the water in the hull at any time. The post or hollow standard is preferably threaded into the base plate or bracket 2, as shown at 5, whereby it may be easily removed when necessary.

Within the post or standard 1 is slidably mounted a bar or rod 6 to the lower end of which is secured, in any desired manner, a float 7 which is preferably a hollow body having a wide base 8 so as to present an extended surface to the action of the water. In order that this float or air chamber may be protected from injury by contact with

any objects which may happen to be floating in the water, I secure to the frame of the vessel or to the lowest deck or flooring thereof a cage 9 which may be of any foraminous or perforated construction and which will preferably be constructed of stout wire netting in order that the water may circulate freely therethrough. The top of the cage is open, as clearly shown in Fig. 1, so as to offer no obstruction to the free rise and fall of the float and the rod or bar 6 carrying the same. In the base plate or bracket 2 and in the deck 10 of the vessel, I form registering openings or passages 11 through which may pass a lifting rod or wire 12 which has its lower end attached to the float 7, as shown at 13, so that the float and the bar 6 may be raised and lowered at will to test the operativeness of the apparatus. Secured around the post or standard 1, near or at the upper end thereof, is a collar 14 which is insulated from the post by a band 15 of vulcanite or other insulating material. At any convenient point in this collar 14, I provide a binding post 16 to which an electric conductor 17 is attached. In the master's cabin or at some other point of the vessel, where it may be very readily observed, I provide a signal board 18 upon which is mounted a bell or similar alarm 19 and a plurality of lamps 20. Any number of these lamps may be provided and in the present instance I have illustrated four, the said lamps corresponding to the port and star-board sides of the vessel and to the fore and aft positions. The conductor 17 is connected with one terminal 21 of the lamp circuit. A battery or other source of electrical energy, indicated at 23, is connected by a conductor 24 with the bell 19 and a conductor 25 connects the bell with the terminal 26 of the lamp. To the upper end of the bar or rod 6, I secure an indicator finger 27 which is insulated from the bar and from the post by vulcanite or other material, indicated at 28, and to the said indicator finger, I secure one end of a conductor 29 which leads to the battery 23. It will be readily understood that as many gages will be provided as may be desired and that each gage will be connected with a lamp corresponding to the position of the gage in the vessel, each lamp being in circuit with the bell or other alarm in substantially the manner indicated and just described. The operation of the device will be readily understood. As

the water rises or falls in the hold of the vessel, the float 7 will, of course, be caused to ascend or descend and the indicator bar or rod 6 will cause the finger 27 to play correspondingly past the gage 4, thereby showing, at all times, the exact height of the water in the hold. The collar 14 may, of course, be set at any desired point of the post 1 so that an alarm may be sounded at any predetermined height of water in the vessel. When the water reaches the said predetermined height, the indicator finger 27 will be carried against the collar 14 and the electric circuit will be thereby closed so that the lamp will be ignited and the alarm sounded. A glance at the signal board will show the master or other officer in charge the location of the high water and the pumps may be manned accordngly or other action taken to prevent sinking or other damage to the vessel.

My device is obviously simple in its construction and may be applied to any vessel at a very low cost.

It is to be understood that the apparatus

may be provided with a circuit closer at a low point or near the base of the standard so that it may be applied to tanks or reservoirs for use as a low-water alarm.

Having thus described the invention, what is claimed as new is:

1. In an apparatus for the purpose set forth, the combination of a post, an indicator bar playing in the post, a float carried by said indicator bar, and a lifter secured to the float and extending upwardly therefrom adjacent the indicator bar.

2. The combination of an indicator post, a collar secured about and insulated from the post and forming a contact member, a float, an indicator bar rising from the float and guided by the post, an indicator finger forming a contact member carried by and insulated from said bar and playing over the post to be carried into contact with the collar on the post, and means for guiding the finger in a rectilinear path.

In testimony whereof I affix my signature.

CHARLES R. FORD. [L.S.]
